UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

BOILER-FEEDING MEANS.

1,236,154.

Specification of Letters Patent. Patented Aug. 7, 1917.

Application filed November 26, 1913. Serial No. 803,177.

To all whom it may concern:

Be it known that I, WILLIAM L. R. EMMET, a citizen of the United States, residing at Schenectady, county of Schenectady, State 5 of New York, have invented certain new and useful Improvements in Boiler-Feeding Means, of which the following is a specification.

The present invention relates to means for feeding liquid to boilers and more especially to those intended for generating vapor from liquids having high boiling points, such for example as mercury. Owing to the cost of such liquids and in the case of mercury to 15 its great weight for a given bulk, it is important to so arrange the boiler that the total amount of liquid for a given vapor output be reduced as much as possible. Reducing the amount of liquid, while it results in 20 a saving in cost and weight and hence is highly advantageous, introduces certain complicated problems in the way of maintaining an active circulation, regulating the supply of fluid to the different generating elements, 25 when operating in multiple, and in preventing one element of the boiler which for some reason may be cooler than another from acting as a condenser for the vapor generated by a hotter element or elements. The problem of maintaining an active circulation 30 when mercury is the substance used is greatly increased due to the high temperature of the fire. For example, the gases may have a temperature of 2400° F. in the furnace. Obviously a failure of the liquid feeding means under these circumstances would 35 greatly endanger the tubes even if the interruption was only for a very brief interval of time.

40 My invention has for its object to provide a boiler feeding means which will satisfy the exacting requirements above specified, and for a consideration of what I believe to be novel and my invention, attention is directed to the accompanying description and claims appended thereto.

In the accompanying drawing which is 45 illustrative of my invention, Figure 1 is a diagrammatic view of a boiler or generator 50 comprising a plurality of vapor generating elements together with means for feeding liquid thereto, and Fig. 2 is a sectional view of the upper end of one of said elements.

55 As my invention is intended especially for use with boilers generating mercury vapor

to be utilized in a turbine it will be described with that in view. In the power system intended to utilize my present invention, the exhaust vapor from the turbine enters what may be termed a condenser-boiler; *i. e.*, a device in which the heat given up by the mercury vapor in condensing is utilized to boil water and generate high pressure steam, the latter being used in a steam turbine of suitable construction. The 60 condensed mercury from the condenser-boiler is returned to the mercury vapor generator by means of gravity, said generator being located below the other parts.

The boiler is composed of a number of 70 vapor generating elements 5 arranged in multiple relation as regards the supply of liquid and also in multiple relation as regards the delivery of vapor to the main 6, the latter leading to a turbine or turbines 75 of any suitable construction, for converting the energy of the vapor into useful work. The boiler elements can be made in a variety of ways. As shown each comprises a header 7 from which depend a relatively large number of vapor generating tubes 8. These tubes may be closed independently at their lower ends or open into a header 9. When closed independently each tube will have an inner open ended tube through which mercury flows from the top to the bottom. In the pipe connecting each element with the discharge main is an outwardly opening check valve 10 having a spring 11 or other means tending to close it. These valves permit vapor to pass from the elements to the main 6 but prevent the passage of vapor from one element to another through the main. The system described is intended to operate at low pressure, say atmospheric or 95 slightly above it for example. At atmospheric pressure mercury vaporizes at a temperature of about 677° F., and condenses in a vacuum of 28" at about 457° F. Without these check valves it is evident that if 100 the temperature of one of the vapor generating elements for any reason, fell substantially below the boiling point of the fluid, it would act as a condenser for the vapor generated by the other element or elements. 105

Mercury is fed to the several generating elements by gravity from the pipe 12 which receives it from the condenser 13 of the turbine or other prime mover. The pressure of the mercury in this pipe is superior to 110

that of the vapor in the said elements. Connected to the pipe is a reservoir 14 which supplies any deficiency due to leakage, etc. From the pipe 12 short pipes 15 discharge into the vapor chests or headers 7 subject to the control of valves. Below each pipe 15 is a well 16, Fig. 2, that extends across the end of the chest, and at suitable points is provided with notches 17 through which the mercury flows into the main portion of the vapor chest. The lower wall of the chest is inclined so as to permit of an accumulation of mercury at one end thereof. The tubes 8 are attached at their upper ends to said wall and mercury is free to flow into them and the vapor to pass therefrom into the chest or header. At one end of the chest is a float 18 that rests on the body of mercury therein and is connected to a bell-crank lever 19, the latter being carried by a support 20. To the upper arm of the lever is attached a rod 21, the other end of which is connected to the arm of a valve 22 in the supply pipe. The valve controls the admission of mercury to the chest and its position is determined by the float 18.

The amount of liquid used in each generating element is purposely small to reduce the total cost of the mercury and also to reduce weight, and hence liquid must be fed to it continuously since otherwise it would be driven out in the form of vapor in a very short time and the parts subjected to destructive heat through lack of liquid. The arrangement of the pipe 12, the pressure of which is above that in the chest as before stated, the valve 22 and float 18 provide for this and insure continuous delivery of liquid in sufficient quantities to all the elements. As will be understood all of the elements are similarly provided with devices controlling the feeding of mercury thereto.

If through the failure of one or more of the valves, for any reason, one generating element should receive much more than its proper share of mercury a conduit 25 is provided for each element that opens into the chest at about the normal level of the mercury. The lower ends of the conduits are connected to a header 26 located at a somewhat lower level than the generating elements. Due to this arrangement one boiler can overflow into the other but the mercury which will always stand in the header and conduits will prevent the passage of vapor from one to the other. In other words, the column of the mercury in said conduits is of such length that it acts as a seal to prevent transfer of vapor from one element to another, while permitting an equalization of the mercury levels in all of said elements.

It will be noted that all of the generating elements operate in multiple both as regards the reception of liquids and the delivery of

vapor, which is desirable in a large installation, and that means are provided for regularly feeding each element with an amount of mercury proportioned to the vapor which it produces. Also that all of the elements receive mercury from a source which is subject to a certain definite gravity pressure and under the control of float actuated valves, each of said floats being located in a portion of the generating unit where the mercury is normal and of appreciable depth. A rise of mercury in one element will therefore temporarily decrease or interrupt the supply and a fall increase it.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In combination, a generator for liquids having high boiling points comprising a plurality of vapor generating elements, a main into which the elements discharge in multiple, a non-return valve between each element and the main to prevent one element from acting as a condenser for another, a conduit feeding liquid under gravity to said elements, and means responsive to the level of the liquid in the elements for regulating the admission of liquid thereto.

2. In combination, a generator for liquids having high boiling points comprising a plurality of vapor generating elements each having a header, a main connected with the headers into which the elements discharge in multiple, a conduit feeding liquid in multiple under gravity head to said elements, and means responsive to a condition of the liquid in said elements for regulating the admission of liquid thereto.

3. In combination, a generator for liquids having high boiling points comprising a plurality of individual vapor generating elements, discharge conduits for the elements, means feeding liquid to the elements, and conduit means connected to the several elements at about the normal level of the liquid therein and communicating with a common header, said conduit means containing a sufficient body of liquid to prevent the transfer of vapor from one element to another.

4. In combination, a generator for liquids having high boiling points comprising a plurality of individual vapor generating elements, discharge conduits for the elements, conduit means feeding liquid to the several elements under gravity head, a float controlled valve for each element regulating

the passage of liquid from said means to said element, and a non-return valve in each vapor discharging conduit to prevent one element receiving vapor from another.

5. In combination, a generator comprising a plurality of vapor generating elements arranged in multiple as regards the reception of liquid and the delivery of vapor, a vapor receiving main that is common to said elements, a non-return valve between each element and the main, a main supplying liquid to all of the elements, a float valve for each element controlling the admission of liquid thereto, and conduit means connected to all 10 of the elements at about the liquid level thereof, said means extending to a point below the elements and containing a sufficient body of liquid to prevent the transfer of vapor from one element to the other while 15 permitting liquid to be so transferred.

6. In combination, a mercury vapor generator comprising a plurality of individual units, a main into which the elements discharge vapor in multiple, a non-return valve 25 between each unit and the main, a main supplying liquid mercury to the elements under gravity head, a reservoir in open communication with the mercury supply main, and means controlling the amount of mercury 30 admitted to the individual elements.

7. In combination, a generator for liquids having high boiling points comprising a plurality of vapor generating elements, each having an upper header with depending

tubes connected thereto, a main, conduits 35 connecting the headers to the main in multiple, a conduit for feeding liquid by gravity to each of said upper headers, and means controlled by the liquid in the headers for regulating the admission of liquid thereto. 40

8. In a mercury boiler, the combination of a plurality of pairs of spaced headers, tubes connecting the headers of each pair, a discharge main, conduits connecting one header of each pair to the discharge main, 45 non-return valves in said conduits, overflow pipes connected with the last named headers, and a common conduit into which they connect.

9. In a mercury boiler, the combination of 50 a plurality of pairs of spaced headers, tubes connecting the headers of each pair, thereby forming a plurality of mercury vapor generating elements, a discharge main, conduits connecting such mercury vapor generating 55 elements to said main, a header located at a level lower than that of the vapor generating elements, and pipes connecting each vapor generating element to said last named header, said pipes connecting with the vapor 60 generating elements at about the normal level of the liquid therein.

In witness whereof, I have hereunto set my hand this 25th day of November, 1913.

WILLIAM L. R. EMMET.
